UNITED STATES PATENT OFFICE.

HARRY H. HONIGBAUM, OF RICHMOND HILL, NEW YORK.

RETAINER FOR STRIP SHINGLES.

Application filed June 27, 1923. Serial No. 648,138.

To all whom it may concern:

Be it known that I, HARRY H. HONIGBAUM, a citizen of the United States, residing at Richmond Hill, county of Queens, 5 and State of New York, have invented a certain new and useful Retainer for Strip Shingles, of which the following is a specification.

This invention is a retainer for strip shingles, and the object of the invention is to provide a simple and economical device which may be rapidly applied to a roof during the laying of shingles thereon and which will have the purpose not only of securing the shingles tightly to the roof, but will furthermore facilitate the alinement of successive courses and also preclude curling or flapping of the weather edges of the shingles.

10 It is well known that composition strip shingles have a tendency to flap in the wind and also to curl at their weather edges after a relatively short period on a roof, and, moreover, considerable care is required in 15 the laying of these strip shingles in order that the successive courses will properly line up and that the strips of each separate course will be properly alined longitudinally of the roof.

20 The device of the present invention fulfills the requirements of properly positioning successive courses while they are being laid and without necessitating the employment of chalk lines, straight edges or other 25 expedients and furthermore serves to hold the shingles firmly to the roof throughout their entire extent after the shingles have been laid.

The device of the present invention in its 30 preferred practical form consists of a strip of sheet metal, one end of which is slit to provide three tongues, two of which are turned down at right angles to the body of the strip and the central tongue of which 35 is turned up for a distance substantially equal to the thickness of the roofing material and then bent at right angles so that said bent over portion will overlie the body of the strip and be substantially parallel to 40 the face thereof. The strip is perforated near its opposite end and is of less width than the width of the slot of a strip shingle.

In use one of these devices is associated 45 with each slot of the strip shingles of each course, the body of the metallic strip being laid upon the shingle adjacent each slot or

cut out therein and in such manner that the downwardly extending tongues will project downwardly into the cut out, while their faces will abut with the base of the cut out. 60 The device having been brought into this position, it is nailed by a single nail to the roof and this nail passes through the device through the body of the strip shingle and into the roof boards. One of the devices is 65 associated with each cut out of each strip of shingles, so that when the next course of shingles is laid, the tabs of the shingles of said second course are received beneath the upstanding tongues of the several devices 70 and are precluded from flapping or curling.

Features of the invention, other than those specified, will be apparent from the hereinafter detailed description and claims, when read in conjunction with the accompanying drawings.

The accompanying drawings illustrate one practical embodiment of the invention, but the construction therein shown are to be understood as illustrative, only, and not as 80 defining the limits of the invention.

The figure shows four devices embodying the present invention in perspective and in the position which they occupy on a roof, a fragmental view of the shingles of which 85 roof is shown associated with the invention.

The device of this invention is constructed of a strip of sheet metal 1, one end of which, in the process of manufacture, is slit to provide three tongues. The central tongue is 90 made longest, while the two lateral tongues are made somewhat shorter and all of said tongues are thereupon bent after the manner shown in the drawings. The two lateral tongues 2 are bent downwardly and are of 95 a length substantially equal to the thickness of a strip of composition shingle material. The intermediate tongue 3 is bent upwardly for a distance substantially equal to the thickness of such composition material and 100 thereafter bent longitudinally of the device and in parallel relation to the body thereof to form a keeper. The opposite end portion of the strip is perforated as at 4.

In practice, the strip may vary in size, 105 but when used in conjunction with strip shingles, the device is preferably not over one-half inch wide, this being the width of the cut out portion 5 of the conventional strip shingle.

110 The manner of employing the device is as follows. In laying a course of shingles on a

2
roof, the successive strip shingles are secured in place by as many of the present devices as there are cut outs in the strips. That is to say, one device cooperates with each cut out 5 of the strip shingle in such manner that the body portion of the device is laid on the top of the shingle with the tongues 2 extending into the cut out 5 and abutting the blind end of the cut out. After the device has 10 been thus positioned, a nail 6 is driven through the perforation 4. In ordinary strip shingles, there are several cut outs and in laying said shingles, one of my devices is associated with each cut out and the nails 15 6 serve not only to secure the device in place, but also to simultaneously secure the shingles to the roof. After one course of shingles has been laid in the manner described, the next course is laid in the same way, but the 20 laying of this next course is facilitated by the holding devices of the preceding course, since the tabs of the shingles of the succeeding course are brought in the process of laying to underlie or extend beneath the keepers 25 3 of the holding devices of the preceding course. Inasmuch as the cut outs in the shingles of the preceding course accurately position the holding device thereof, it will be apparent that the keepers of such holding 30 devices will automatically position the strip shingles of the succeeding course, so that all the shingles of the succeeding course will be automatically aligned longitudinally of the roof. This is a marked advantage since it 35 obviates the necessity of employing chalk lines, straight edges or other extraneous means in the proper lining up of shingles of any particular course.

In practice, the keepers 3 are so proportioned that the tabs of a succeeding course 40 may be readily received beneath such keepers and this being the case, said keepers will, after the roof is finished, not only preclude flapping of the tabs in the wind, but will 45 hold down the weather edges of such tabs against curling, so that the shingles will at all times lay flat and produce a neat and pleasing appearance.

In practice, the holding devices constructed in accordance with this invention 50 are made relatively small, this being especially true of the tongues 2 and 3, so that they will not be perceptible on a roof. In fact, they are so small in practice that 55 they are practically invisible except at very close range. The devices may be made of

any suitable material, preferably non-corrosive, and may be if desired painted or dipped in coloring material harmonizing with the strip shingles for which they are 60 adapted for use, so that they will be absolutely invisible.

The invention is especially intended for employment in conjunction with strip shingles and I am aware that it may be used 65 in conjunction with individual shingles, and the invention is therefore to be construed as commensurate with the appended claims.

Having thus fully described the invention, what I claim as new and desire to secure by 70 Letters Patent is:

1. A holding device for strip shingles embodying a metallic strip provided at one of its ends with a downwardly extending tongue adapted to extend into the cut out 75 of a strip shingle and to abut the blind end of said cut out and also provided at the same end of the metallic strip with an upstanding tongue adapted to receive beneath it a tab of the next course of strip shingles, 80 said tongues being positioned at the same point in the length of the strip.

2. A holding device for strip shingles embodying a metallic strip provided at one of its ends with downwardly extending tongues 85 adjacent each lateral edge of the strip and adapted to extend into the cut out of a strip shingle and to abut the blind end of said cut out, said metallic strip being further provided with an intermediate upstanding tongue adapted to receive beneath it a tab of the next course of strip shingles, all 90 of said tongues being positioned at the same point in the length of the strip.

3. A holding device for strip shingles embodying a metallic strip provided at one of its ends with three tongues, all of which 95 are positioned at the same point in the length of the strip, the two outside tongues being bent downward to form positioning stops adapted to extend into the cut out of a strip shingle and to abut the blind end of said cut out, and the intermediate tongue being bent upwardly and thereafter returned 100 upon the metallic strip in substantially parallel relation thereto, for the purpose of providing a keeper adapted to receive beneath it a tab of the next course of strip shingles.

In testimony whereof I have signed the 110 foregoing specification.

HARRY H. HONIGBAUM.
